UNITED STATES PATENT OFFICE

132,993

DESIGN FOR A BINGO SHEET OR SIMILAR ARTICLE

Erwin S. Lowe, Brooklyn, N. Y.

Application May 1, 1942, Serial No. 106,770

Term of patent 7 years

To all whom it may concern:

Be it known that Erwin S. Lowe, a citizen of United States and resident of Brooklyn, in the county of Kings and State of New York, has invented a new, original, and ornamental Design for a Bingo Sheet or Similar Article, of which the following is a specification, reference being had to the accompanying drawing, forming part thereof, and in which,

Fig. 1 is a top plan view of a bingo sheet, embodying my new design; and

Fig. 2 is a side elevational view thereof.

I claim:

The ornamental design for a bingo sheet or similar article, substantially as shown.

ERWIN S. LOWE.
